(57) **CLAIM**

The ornamental design for a plastic container, as shown and described.

DESCRIPTION

FIG. 1 is a top-rear-right perspective view of a plastic container showing an embodiment of the claimed design; FIG. 2 is a top-front-left perspective view of a plastic container showing the embodiment of the claimed design; FIG. 3 is a rear elevational view of FIG. 1; FIG. 4 is a front elevational view of FIG. 1; FIG. 5 is a right side elevational view of FIG. 1; FIG. 6 is a left side elevational view of FIG. 1; FIG. 7 is a top plan view of FIG. 1; and, FIG. 8 is a bottom plan view of FIG. 1. The broken lines shown in the drawings illustrate portions of the plastic container that form no part of the claimed design.
